(57) **CLAIM**

The ornamental design for a sterilization box for medical devices, as shown and described.

DESCRIPTION

1. Sterilization box for medical devices

1.1 : Perspective

1.2 : Front

1.3 : Back

1.4 : Left

1.5 : Right

1.6 : Top

1.7 : Bottom

This device relates to medical container used for storage and sterilization of medical devices.

The broken lines illustrate portions of the sterilization box for medical devices that form no part of the claimed design.

1 Claim, 7 Drawing Sheets
